SHUTTLE REMOVERS FOR EMBROIDERING MACHINES

Karol Lindner, St. Petersburg, Fla.

Application April 15, 1958, Serial No. 728,601

10 Claims. (Cl. 112—186)

This invention relates to shuttle removers for embroidery machines.

As was pointed out in my prior Patent No. 2,694,374 of November 16, 1954, an embroidery machine comprises a large number of aligned shuttle boxes which rest on a shuttle box bar. Each shuttle box slidably supports a shuttle which is caused to reciprocate substantially vertically during operation of the machine. Each shuttle contains a bobbin, the thread of which becomes exhausted as embroidery operations continue. Accordingly, it is necessary to replace such bobbins periodically. In actual practice, instead of replacing the bobbin in the shuttle, a preloaded shuttle is substituted for the exhausted one. Shuttles are now replaced by lifting them out of the shuttle box and substituting a fully loaded shuttle. This is a time consuming and tedious operation since a conventional 15 yard machine has more than 550 shuttle boxes. In my prior patent I disclosed a mechanism for facilitating the feeding of shuttles to the shuttle boxes. In the instant invention, however, I disclose a device for removing a large quantity of exhausted shuttles from the shuttle boxes so that loaded ones may be replaced therein.

The invention comprises an elongated device having a number of inclined cut-outs each of which is adapted to fit over the upper end of a shuttle when the shuttle is advanced to its extreme upward position in the machine. The device embodies means for engaging the upper tip ends of a large number of shuttles so as to permit their removal from the shuttle boxes. Means are also provided to disengage the shuttles so as to permit them to be released and dropped into a container of any kind. The tip or pointed ends of the shuttles include an inside recess as is well known in the art. My engaging means enter this recess and comprise releasable spring locks for insuring a good grip on the shuttles.

The invention will be further understood from the following description and drawings in which:

Figure 1 is a fragmentary, vertical cross-sectional view illustrating the application of the removing device to the shuttles of the embroidery machines;

Figure 2 is an end view of the device in elevation;

Figure 3 is a fragmentary, cross-sectional view as taken along the line 3—3 of Figure 2;

Figure 4 is an enlarged, cross-sectional view as taken along the line 4—4 of Figure 3;

Figure 5 is an enlarged cross-sectional view as taken along the line 5—5 of Figure 3;

Figure 6 is an enlarged cross-sectional view as taken along the line 6—6 of Figure 3;

Figure 7 is a perspective view of an arm and arm holder used in engaging the shuttle;

Figure 8 is a front elevational view of a modified embodiment;

Figure 9 is a side elevational view thereof;

Figure 10 is a bottom plan view of the above mentioned modified embodiment;

Figure 11 is a cross-sectional view as taken along the line 11—11 of Figure 10;

2

Figure 12 is a cross-sectional view as taken substantially along the line 12—12 of Figure 11;

Figure 13 is a cross-sectional view as taken along the line 13—13 of Figure 11; and

5 Figure 14 is a perspective view of the engaging arm for the shuttle.

Referring now to Figures 1 to 7, the body of the device is rectangular and box like in appearance as will be noted from Figures 2, 5 and 6. Referring to Figure 10 2, it comprises a bottom section 15 connected to a side section 16 to form the rectangular structure. Panels 17 and 18 serve to enclose and protect the mechanism. The bottom section 15 is formed with a number of parallel inclined chambers 19, each of which slidably receives an 15 arm holder 20 having a vertical slot 21 at the bottom of which is secured an arm 22 as noted in Figure 7. The exposed end of arm 22 has a concavely arcuate lower end which, as will be noted hereinafter, presses complementarily against the shuttle upper end.

20 Each chamber 19 is formed with a floor 23 (Figure 5) having a central slot-like opening which slidably receives arm 22 therethrough.

The lower end of bottom section 15 is formed with a 25 series of cut-outs 24 which are below floor 23 and each of which communicates with one of the above mentioned central slots thereof. As observed in Figure 3, cut-outs 24 are shaped like inverted V's with one leg of the V concavely arcuate and the other leg inclined about 15° from a vertical plane so as to receive and conform to the 30 upper end of the shuttle as will hereinafter be explained.

Said inverted V shape results from a cross-sectional view of the cut-outs 24. Actually, as observed in Figure 5, the cut-outs 24 have rounded walls conforming to the shape of the rear upper end of the shuttle. Accordingly, the rear upper end of the shuttles 25, as noted in Figure 1, will be snugly received in the cut-outs 24.

35 Side section 16 is formed with an upper enlargement 26 which rests upon the top level of bottom section 15 as observed in Figure 2. Upper enlargement 26 is formed with a plurality of inclined parallel grooves 27 defined by spaced bosses 28. An arm holder 20 is slidably disposed in each groove 27 as noted in Figure 1. The inclination of the grooves 27 and bosses 28 is about 15° from vertical. A slideable bar 29 passes through all 40 of the vertical slots 21 so as to suspend each arm holder upon bar 29.

45 Bar 29 is horizontally slidable in elongated vertical slot 30 which is formed along the entire length of enlargement 26 of side 16. The extent of slidability is controlled by horizontal, closed slots 31 which engage fixed pins 32. Thus, bar 29 may slide horizontally back and forth pursuant to the length of horizontal slots 31.

50 Bar 29 constitutes a cam device for vertically actuating the arm holders from a lowered position of the arms 55 22 for engaging the shuttles as will hereinafter be described, to a raised position for disengaging the shuttles when it is desired to release them. Bar 29 is manually slidably actuated and is formed with a fingerhold cut-out 33 to facilitate such actuation. The bar is formed 55 with a series of aligned cut-outs 34 having one wall 35 which is parallel to the inclined grooves 27 and having an opposing cam wall 36 which is inclined rearwardly relative thereto.

60 It will be observed that the rear wall of the cut-outs 65 24 is formed with an integral projection 37. This projection 37 cooperates with the arcuate lower end of arm 22 in firmly engaging a shuttle upper end.

65 As is well understood by those skilled in the art, each shuttle 25 comprises a hollow chamber 38, the upper end 70 of which is tipped or pointed. An inner wall, not shown, is hinged at the bottom of the opening of chamber 28

and serves to close the shuttle. This inner wall does not reach the inner tipped end of the shuttle so as to leave a slight inner recess 39 at such tipped end as observed in Figure 1. The arm 22 serves to depress and wedge the upper end of the shuttle against the projection 37 which enters the recess 39 and thus firmly engages the upper end of the shuttle. When the arm 22 is in a rest position, the shuttles fit freely in the recesses 39 notwithstanding the presence of integral projections 37 which are formed on the rear walls of the cut-outs 24. When, however, the arm 22 is lowered it wedges the upper end of the shuttles against the projections 37.

Bottom section 15 is connected to front section 16 as by screws 40 which also secure the rear panel 17 to the assembly.

The device as above described is employed as follows:

Referring to Figure 1, the embroidering machine is provided with a large number of aligned shuttle boxes 41 each of which has a vertical planar back 42 all as well understood. The shuttle 25 slides upon chute 43 of shuttle box 41 during the operation of the machine. When the shuttle 25 is actuated to an extreme upper position as illustrated in Figure 1, its upper end is accessible for removal. It is in this position that my device is employed.

The device may comprise any convenient number of cut-outs 24. For example, let us assume that it has 15 such cut-outs. The device is positioned and longitudinally arranged that all the cut-outs 24 embrace the upper tip ends of the shuttles 25. Since the shape of the cut-outs 24 are complementary to such tip ends, the shuttles 30 will be received snugly in such cut-outs.

Normally, each arm holder 20 has the upper end of its slot 21 engaged by the upper end of wall 35 as illustrated in Figure 3 so that said arm holders are disposed in their uppermost position. In this position, the arms 22 are held upwardly and outwardly of the cut-outs 24, thus permitting the cut-outs 24 to snugly embrace the upper or tip ends of the shuttle 25. Accordingly, when the bar 29 is actuated from the outward position illustrated in Figure 3, to an inward position illustrated in Figure 1, the arms 22 will descend because the upper end of the slots 21 are now in the valley of cut-outs 34. Arms 20 thus drop not simply by gravity but through the influence of springs 45. These arms 22 then push against the upper rear of the shuttles as illustrated in Figure 1 and force the projections 37 into the inside recesses 39. This effects a firm grasp upon all the shuttles.

The user will then lift the entire device with all the shuttles 25 firmly held and suspended therefrom. He will then place the device over a container and will retract bar 29. This will raise all the arm holders and arms whereupon the shuttles 25 will drop through force of gravity into the container. The shuttle boxes may then be reloaded with filled shuttles.

Referring now to Figures 8 to 13, a modified form of the device is shown which effects the same results. It will be observed that the height of this device is less than that of the first embodiment, the reason being that the arms, as will be shown hereinafter, swing pivotally rather than reciprocate vertically. In this device, the body 50 has side plates 51 and 52 and a top plate 53. Body 50 may be of one piece construction, but for facility in producing, it is formed with adjacent sections 50a, 50b, 50c, and 50d, etc. which are horizontally aligned. The underside of body 50 is formed with cut-outs 52 which are complementary in shape to the upper end of the shuttle as hereinbefore described.

The means for actuating the arms comprises a bar 54 bearing a handle 55 at one end thereof. Bar 54 is elongated and has a plurality of spaced holes 56 formed therein. Bar 54 slides horizontally in a well formed at the upper end of body 50. The well is covered by means of the top plate 53.

Arms 57 are pivotally mounted in each section of body 50, such arms serving to engage the shuttles. Each arm

57 is provided with a hinge pin 58 which may be integral therewith or secured thereto. As observed in Figure 13, hinge pins 58 are disposed in openings in sides of body 50, such openings serving as bearings.

Each arm 57 is provided with a reduced upper end 59 which is engaged by the openings 56 of bar 54 so that horizontal reciprocation of bar 54 causes the arms to pivot about their pins 58.

10 Each of the arms 57 is provided with an integral projection 60 at the lower end thereof. This projection serves essentially the same function as the projection 37 of the first embodiment save that in this case, it is made integral with the arms.

15 As observed in Figures 11 and 12, all the arms 57 are pivotally mounted within body 50, the upper reduced ends 59 of the arms all being engaged by correspondingly spaced opening 56 in the bar 54. Integral with each arm 57 is a spring retaining pin 61. A spring 62 is mounted on each pin 61 the other terminal of the spring being retained in an opening 63 formed in the body 50.

20 Referring to Figure 11, when a shuttle 25 has its upper or tipped end disposed within the cut-out 52, in substantially the same manner as hereinabove described, its inside recess, as above described, will be in a position to be engaged by the projection 60 of each arm. The normal action of the spring 63 is to bias the arms 57 in such a direction that the projections 60 enter the inside upper recesses of the shuttle. At the same time, the lower ends of arm 57 push against the shuttle so as to urge its convexly rounded upper, outer wall against the concavely rounded cut-outs 52 so as to permit the projection 60 to effect a good grip with the inside recess of the shuttle.

25 The last mentioned embodiment will be operated by initially sliding bar 54 inwardly against the action of the springs 63. The device will then be deposited over as many shuttles as there are cut-outs to accommodate them. The operator will then release the bar 54 or, preferably, actually pull it outwardly so as to permit the springs 63 to actuate the arms 57 to a shuttle engaging position. 30 At this time the shuttles have been found to be firmly engaged and the device can be lifted from the machine, with all the shuttles being suspended therefrom, whereupon they may be released as aforesaid, into a suitable container.

35 It will be seen from the foregoing that I have devised a machine which will simply and reliably remove a large number of shuttles in a simple, substantially single action. The bottom cut-outs are spaced pursuant to the normal spacing of the shuttles 25 in the machine as illustrated in Figure 1 so that the shuttles will accurately fit into such cut-outs so as to be engaged by the arms in the projections. The body of the device may be formed of wood, plastic, metal, or any equivalent material.

40 There has been shown what is now considered preferred embodiments of the invention but it is obvious that numerous changes and omissions may be made without departing from its spirit.

45 What is claimed is:

1. A shuttle removing device for embroidering machines, said device comprising a body having a series of cut-outs formed therein, each of said cut-outs being of a shape to receive the upper end of a shuttle, a projection disposed in said cut-outs and adapted to enter a recess in the upper end of the shuttle for engaging the shuttle, and manually actuatable means for effecting said engagement.

60 2. A shuttle removing device for embroidering machines, said device comprising a body having a series of cut-outs formed therein, each of said cut-outs being of a shape to receive the upper end of a shuttle, a projection disposed in said cut-outs and adapted to enter a recess in the upper end of the shuttle for engaging the shuttle, an arm for urging said projection into engagement with said shuttle upper end, and a manually controlled bar actuating said arm.

65 3. A device according to claim 2 and wherein each

of said cut-outs are of substantially inverted V-shape in longitudinal cross-section with one leg of the V concavely arcuate and the other straight and inclined from a vertical plane.

4. A device according to claim 3 and including spring means for urging said arm into engaging position with said projection. 5

5. A device according to claim 4 and wherein said arm has a concavely arcuate lower end which presses against said shuttle upper end from one side of said cut-out, 10 said projection being formed on said body on the other side of said cut-out.

6. A device according to claim 5 and wherein said body is formed with an enlargement on one side thereof, a series of inclined, parallel chambers formed in said enlargement, a holder for each arm slidably disposed in each of said chambers, each of said chambers being formed with a floor having a slot formed therethrough, said arm being secured to said arm holder and extending into said floor slot, said floor slot communicating with said cut-outs, said bar being manually slidible, and a slot in each of said arm holders through which said bar extends, said bar comprising means for actuating said arm holders and arms out of engagement with the shuttles when the bar is manually actuated. 15 20 25

7. A device according to claim 6 and wherein said bar is formed with cam walled cut-outs, the cam walls engaging said arm holder through the arm holder slots and actuating said arm holders and arms in a substantially vertical direction when said bar is actuated horizontally.

8. A device according to claim 2 and wherein said arm and said projection are integral.

9. A device according to claim 8 and wherein said arm is pivotally mounted in said body, and spring means for normally urging said arm and said projection into engagement with said shuttle upper end, said bar being slidably connected to all of said arms for actuating them against the action of said spring means.

10. A device according to claim 9 and wherein each of said cut-outs are of substantially inverted V-shape in longitudinal cross-section with one leg of the V concavely arcuate and the other straight and inclined from a vertical plane.
